UNITED STATES PATENT OFFICE

ERNEST WILLIAM JOHNSON, OF LONDON, ENGLAND, ASSIGNOR OF ONE-HALF TO LUVAX
LIMITED, OF LONDON, ENGLAND, A BRITISH COMPANY

HYDRAULIC SHOCK ABSORBER

Application filed December 14, 1928. Serial No. 326,120.

This invention is for improvements in or relating to hydraulic shock-absorbers and more particularly to shock-absorbers of the type shown and described in the specification of United States Letters Patent No. 1,578,319, dated 18th July, 1925.

It is an object of the present invention to provide a shock-absorber which will be robust and cheap to manufacture.

It is another object of the present invention to provide a shock-absorber in which certain parts can be formed as stampings, and in which the parts can be readily assembled without skilled fitting.

It is a further object of the invention to reduce the overall dimensions of such devices whereby their weight and the cost of producing them is also reduced.

Further objects of the present invention will be apparent from the following description of a preferred embodiment of the invention as illustrated in the accompanying drawings in which:

Figure 1 is a perspective view showing, in elevation, a shock-absorber constructed in accordance with the invention;

Figure 2 is a view to a larger scale than Figure 1, showing the device in section along the bent line 2—2 of Figure 3;

Figure 3 is a view showing the device in section along the line 3—3 of Figure 2;

Figure 4 is a detail view showing the device in section along the bent line 4—4 of Figure 3 with certain parts omitted for the sake of clearness;

Figure 5 is a detail sectional view along the line 5—5 of Figure 3, certain parts being omitted for the sake of clearness;

Figure 6 is a similar view to Figure 5 showing a detail modification;

Figure 7 is a view showing a part of the device.

Figure 8 is a detail sectional view of a band, and

Figure 9 is a view similar to Figure 4, but showing a modification.

Like reference numerals indicate like parts in all the figures of the drawings.

The shock-absorber is built up on an end-plate 10 which is formed with holes 11, where-

by it can be mounted in the vehicle-chassis. This plate is formed with a central spigot 12 at the centre of which is a circular bore 13 and which has also a second circular bore 14 located above the central bore 13. The end-plate is further formed with a circular flange 15 which is concentric with the spigot and projects outwardly from the same face of the end-plate.

Mounted on the end-plate is an inner casing 16 which encloses a working chamber 17 for the reception of the working liquid. The inner casing is formed as a pressing and having a cylindrical wall 18 and an annular wall 19 partly closing one end but leaving a central opening which is surrounded by a tubular extension 20 of the end wall 19. The edge where the extension 20 and the wall 19 meet is chamfered off at 21 and the angles between the wall 19 and the wall 20 are rounded off for the sake of strength. The other end of the casing extends radially outwards to form a flange 22, the periphery of which is formed with six equally spaced serrations 23. Carried in the tubular extension 20 is a bearing 24 formed with a collar 25 which abuts against the chamfered surface 21. The outer end of the bearing is threaded and carries a nut 26 which is screwed tightly against the end of the extension 20 so as to hold the bearing in position. The outer surface of the nut 26 is cylindrical and forms a continuation of the outer surface of the extension 20. Journalled in the bearing 24 is a spindle 27, one end of which projects outwardly from the casing 16, and the other end of which is supported in the circular bore 13 in the end-plate 10. A vane 29 is secured to that part 28 of the spindle 27 that lies within the chamber 17 and has the form of a blade having a rounded boss. This boss is shown integral with the spindle, but it may be flexibly secured thereto in any convenient manner.

An abutment 30 is secured within the casing, which is divided into two parts by the abutment and the vane. Referring to Figure 2, it will be seen that the abutment is bounded by two coaxial cylindrical walls 31 and 32, which are in contact respectively with the inner surface of the wall 18 of the casing 16.

and the outer surface of the collar 28, and two radial walls 33 and 34. In order that the abutment should fit accurately it is preferably made as follows:—Steel bar is machined externally to the internal diameter of the casing 16 and is then bored to form a throughway, the diameter of which is the same as the external diameter of the collar 28. After being bored, the bar is cut off into lengths equal to the length of the abutment and divided along radial planes into four abutments in any suitable manner. Each segment so made will have two accurately concentric surfaces which will fit snugly in place. At one end of the abutment a spigot 35 is provided, which spigot is received in the bore 14 in the end-plate 10, and the other end is tapped at 36 and 37 for two screws 38, which project through suitable openings in the wall 19 of the inner casing and hold the abutment thereto. The abutment is formed with a circular bore 39 at its end opposite the spigot 35, a tapped concentric bore 40 of reduced diameter which forms a continuation of the bore 39, and a concentric passage 41 forming a continuation of the tapped bore 40 and terminating near the root of the spigot 35. A passage 42 extends from the bore 40 to the radial surface 34 and a similar passage 43 extends from the passage 41 to the radial surface 33 (see Figures 4 and 7). A ball-valve 44 is located in the bore 40 and is pressed by a spring 45 so as to close the passage 41. An adjusting screw 46 is screwed into the bore 40 and serves both as an abutment for the spring 45 and as a limiting stop of the ball-valve 44. The head of screw 46 is located in the bore 39 and is slotted at 47 to provide means for rotating the screw 46 to adjust the load on the valve.

Referring to Figures 3 and 4 it will be seen that when the vane is rotated counter-clockwise the working liquid can pass freely through the passages 43, 40 and 42 but when the vane is rotated clockwise the valve 44 will prevent any liquid from passing through these passages. The following means are provided for allowing a restricted flow when the vane is rotating clockwise so as to produce the required damping action. Two passages 48 and 49 extend from the bore 39 to the radial surface 33 and the cylindrical surface 32 respectively, and a third passage 50 extends from the passage 49 to the radial surface 34. A tapped hole 51 extends from outside the inner casing 16 through the latter and the abutment and opens into the bore 39. This hole is in alignment with the passage 49 and a screw-threaded needle-valve 52 is received in it. The point of the valve 52 reaches into the passage 49 and obstructs it so as to permit only a restricted flow of liquid through it. When the valve is correctly set, it is locked in position by a lock-nut 53. The valve 52 also

extends through the slot 47 in the adjusting screw 46 so as to lock this latter part against rotation (as shown in Figures 2 and 3).

Mounted on the end-plate 10 is an outer casing 54 which encloses the inner casing and constitutes a recuperator chamber 55 surrounding the working chamber. At its top, the outer casing is provided with an orifice closed by a screw-cap 56 and arranged in alignment with the needle-valve 52. The orifice serves as a filling orifice for the recuperator-chamber and also to give access to the needle-valve so that it may be adjusted.

Means are provided for replenishing the working-chamber 17 with working liquid from the recuperator-chamber 55. Referring to Figures 3 and 4, three shallow recesses 57 are formed in the exterior of the wall 18 of the inner casing towards the bottom thereof, and two similar recesses 59 towards the top thereof. A slot 58 extends from each of the depressions 57 to the inside of the casing and a circular hole 60 extends from each of the depressions 59 to the inside of the casing. The holes 60 are located in that part of the wall 18 which is in contact with the abutment 30, and the latter is formed with two air-vent passages 61 and 62 which are in alignment one with each hole 60. The wall 18 of the inner casing is also formed with a shallow circumferential recess 63 in which is received a band 64 so as to cover the depressions 57 and 59. This band has five conoidal depressions 65, each of which terminates in a hole 66, and which are spaced round the band so as to register one with each of the depressions 57 or 59. In each of the cavities so formed, a ball-valve 67 is received. In order that the band may be correctly mounted on the inner casing it has a locating pip 68 pressed out of it, and the inner casing has a co-operating depression 69 formed in it (see Figure 4). The band is sheathed in lead as shown in Figure 8 in order to provide an oil-tight joint between it and the inner casing, and has its two ends 70 and 71 turned outwardly and secured together by a nut and screw 72 passing through them and clamping the band onto the casing.

Instead of clamping the band 64 in position, the band may be continuous and may be shrunk on, as shown in Figure 9. The valves 67 at the bottom of the casing permit the free passage of liquid from the recuperator chamber 55 to the working chamber, but prevent return movement thereof as described in the aforesaid prior specification. The valves 65 at the top of the casing permit of any air that may leak into the working chamber being forced out of it without allowing any of the working liquid to escape. The provision of the air-vent passages 61 and 62 enables the air-release valves to be high enough up for them not to be covered by the

vane 29 when the latter is in either extreme position.

The outer casing 54 is formed as a stamping and has a substantially cylindrical wall 73 which is formed with six corrugations 74. One end of the outer casing is partly closed by an annular end-wall 75 which is formed with a central tubular extension 76. The other end of the outer casing is open, and this end of the cylindrical wall is turned outwardly to form a flange 77. The bearing 24 and nut 26 extend into and fit snugly within the tubular extension 76. The top of the nut 26 and of the tubular extension 20 is removed, as shown at 78 (Figure 5), so as to form a passage between the nut 26 and the tubular extension 76. Alternatively, as shown in Figure 6, the tubular extension 76 may be indented on its inner surface, as shown at 80, in order to form a similar passage 79. The object of this passage 79 is to allow of any working liquid which may leak from the working-chamber along the spindle 57, and collect within the tubular extension 76, to escape from the tubular extension into the recuperator-chamber. An internal circumferential projection is formed in the tubular extension 76 at 81, and that portion of the extension beyond this projection is threaded externally for the reception of a cap 82. A trough-shaped packing-ring 83 is located between the end of the tubular extension 76 and the spindle 27. Located within the tubular extension and abutting against the projection 81 is an abutment-ring 84, which is formed with a conoidal surface 85 against which one side of the trough-shaped packing-ring abuts and which also bears against the inner surface of the other side of the packing-ring at 86. The arrangement is such that when the cap 82 is screwed down, it presses the packing-ring against the abutment and the latter expands the packing-ring into sealing contact with the spindle.

The spindle 27 has secured to its free end the usual lever 87, the end of which is connected to the axle of the vehicle by a link 88, also in the usual manner.

The shock-absorber is assembled in the following manner:—The bearing 24 is secured in place and the spindle with the vane secured on it is mounted in the bearing. The ball-valve 44 is assembled in the abutment 30 and the load on the valve is adjusted by means of the set-screw 46. The abutment is then secured in position in the inner casing. The ball-valves 67 are placed in the depressions 57 and 59 with the aid of a little grease and the band 64 is slipped into position on the casing and clamped thereon. The needle-valve 52 is then placed in position and adjusted so as to give the required damping action and to lock the screw 46. The open end of the inner casing is then forced under pressure onto the spigot 12 on the end-plate,

and the flange 22 is riveted to the end-plate by means of rivets 89. By means of this spigot-joint between the end-plate and the inner casing, an oil-tight joint between these two parts is ensured. The outer casing 54 is mounted on the end-plate with its corrugations 74 in radial alignment with the serrations 23 in the flange 22 of the inner casing, and is secured thereto by screws 90 passing through the flange 77 in radial alignment with the corrugations 74.

The operation of the device will be readily understood from the above and is the same as that described in the aforesaid prior specification. With the parts arranged as illustrated, the liquid in the working chamber will offer resistance to the movement of the vane in the clockwise direction as viewed in Figures 2 and 4, as the valve 44 will be forced upon its seat, but movement of the vane in the opposite direction will be readily permitted.

It will be seen that with the present invention the various parts can be cheaply manufactured so as to fit accurately together, and that the whole device can be rapidly assembled. It will be noted that owing to the provisions of the corrugations 74 in the outer casing and to the staggered arrangement of the rivets 89 and screws 90, the two casings can be secured to the end-plate 10 by means of flanges without any substantial increase in the dimensions of the device being necessary. It will also be seen that the needle-valve 52 can be readily adjusted to adapt the shock-absorber to the particular vehicle to which it is to be fitted.

It is to be understood that the present invention is not restricted to the precise constructional details described above and that many modifications may be made therein without departing from the scope of the invention.

I claim:

1. A hydraulic shock-absorber comprising an end-plate, an inner casing mounted thereon and constituting a main working chamber for the reception of a working liquid, a vane in said chamber, a spindle secured to said vane and projecting from said chamber, a co-operating abutment secured in said chamber, an outer casing constituting a recuperator chamber, which outer casing is so mounted on said end-plate that the working chamber is nested in the recuperator chamber, and which outer casing has its side walls corrugated to form external depressions therein extending perpendicularly of the end-plate, devices for securing said outer casing to said end-plate, which devices are located in alignment with said depressions, devices for securing said inner casing to said end-plate, which devices are located between said inner and outer casings in staggered relationship to said external depressions, and means for automatically keeping the working cham-

- ber charged with working liquid from the recuperator chamber.
2. A hydraulic shock-absorber comprising an end-plate, an inner casing formed of sheet metal and pressed into shape, which inner casing is mounted on said end-plate and constitutes a working chamber for the reception of a working liquid, a vane in said chamber, a spindle secured to said vane and projecting from said chamber, a co-operating abutment secured in said chamber, an outer casing constituting a recuperator chamber which casing is so mounted on said end-plate that the working chamber is nested in the recuperator chamber, and means for automatically keeping the working chamber charged with working liquid from the recuperator chamber.
3. A hydraulic shock-absorber comprising an end-plate, an inner casing formed of sheet metal, pressed into shape and has its side walls corrugated during the pressing operation to form external depressions therein extending perpendicularly of the end-plate, devices for securing said outer casing to said end-plate which devices are located in alignment with said depressions, devices for securing said inner casing to said end-plate, which devices are located between said inner and outer casings in staggered relationship to said external depressions, and means for automatically keeping the working chamber charged with working liquid from the recuperator chamber.
3. A hydraulic shock-absorber comprising an end-plate, an inner casing mounted thereon and constituting a main working chamber for the reception of a working liquid, a vane in said chamber, a spindle secured to said vane and projecting from said chamber, a bearing for said spindle, which bearing is mounted on said inner casing to extend outwardly therefrom, an outer casing constituting a recuperator chamber, which casing is so mounted on said end-plate that the working chamber is nested in the recuperator chamber, an outwardly directed tubular extension formed in said outer casing, into which extension the free end of said bearing reaches so as to close the inner end thereof, a gland located at the outer end of the extension through which gland the spindle passes, a passage, located between the bearing and the extension, and extending from the space within the extension between the gland and bearing to the recuperator chamber, and means for automatically keeping the working chamber charged with working liquid from the recuperator chamber.
4. A hydraulic shock-absorber comprising an end-plate, a spigot formed in said end-plate, an inner casing, constituting a main working chamber for the reception of a working liquid, which casing is formed as an open ended cylinder and has said spigot forced into its open end under pressure, an outwardly directed annular flange surrounding the open end of said casing, an annular surface on said end-plate against which said flange abuts, rivets passing through said flange and said end-plate to secure them together, a vane in said chamber, a spindle secured to said vane and projecting from said chamber, a co-operating abutment secured in said chamber, an outer casing constituting a recuperator chamber which casing is so mounted on said end-plate that the working chamber is nested in the recuperator chamber, and means for automatically keeping the working chamber charged with working liquid from the recuperator chamber.
5. A hydraulic shock-absorber comprising an end-plate, a spigot formed in said end-plate, an inner casing, open at one end and constituting a main working chamber for the reception of a working liquid, which casing comprises a cylindrical wall, an integral end-wall formed with an opening and partially closing one end of the casing, an integral tubular flange surrounding said opening, and an integral annular flange extending outwardly from the cylindrical wall at the other end of the casing and having its periphery formed with indentations, and which casing has the said spigot forced into its open end under pressure, rivets passing through said end-plate and said flange between said indentations, a vane in said chamber, a spindle secured to said vane and projecting from said chamber, a co-operating abutment secured in said chamber, a bearing for said spindle, which bearing is carried by said tubular flange on the inner casing, an outer casing, constituting a recuperator chamber, which casing is formed as an open ended cylinder, having its cylindrical walls corrugated to form external depressions extending parallel to its axis, and having an outwardly directed flange formed in it at its open end, means for securing said flange to said end-plate, which means are located in alignment with said corrugations and said indentations in the inner case, and means for automatically keeping the working chamber charged with working liquid from the recuperator chamber.
6. A hydraulic shock-absorber comprising an end-plate, an inner casing mounted thereon and constituting a main working chamber for the reception of a working liquid, a vane in said chamber, a spindle secured to said vane, and projecting from said chamber, a co-operating abutment secured in said chamber, an outer casing constituting a recuperator chamber, which casing is so mounted on said end-plate that the working chamber is nested in the recuperator chamber, an air-release passage formed in said inner casing, an oil admission passage formed in said inner casing, a valve-member in each of said passages, and a band formed with a passage to register with said air-release passage and a passage to register with said liquid admission passage and secured on the outside of

said inner casing so as to retain both said valve-members in position.

7. A hydraulic shock-absorber comprising an end-plate, an inner casing mounted thereon and constituting a main working chamber for the reception of a working liquid, a vane in said chamber, a spindle secured to said vane and projecting from said chamber, a co-operating abutment secured in said chamber, an outer casing, constituting a recuperator chamber, which casing is so mounted on said end-plate that the working chamber is nested in the recuperator chamber.

10 said chamber, an outer casing, constituting a recuperator chamber, which casing is so mounted on said end-plate that the working chamber is nested in the recuperator chamber, an air-release passage formed in said inner casing, a liquid admission passage formed in said inner casing, a valve member in each said passage, a band that has a soft face, is formed with a passage to register with said air-release passage and a passage to

15 register with said oil admission passage, and is secured on the outside of said inner casing so as to retain both said valve members in position, and means for contracting said band to clamp it onto the casing.

25 8. A hydraulic shock-absorber comprising an end-plate, an inner casing mounted thereon and constituting a main working chamber for the reception of a working liquid a vane in said chamber, a spindle secured to said vane and projecting from said chamber, a co-operating abutment secured in said chamber, an outer casing constituting a recuperator chamber, which casing is so mounted on said end-plate that the working chamber is nested in the recuperator chamber, an air-release passage formed in said inner casing, an oil admission passage formed in said inner casing, valve member in each of said passages, and a band formed with a passage to register

30 40 with said air-release passage and a passage to register with said liquid admission passage and secured on the outside of said inner casing so as to retain both said valve-members in position, a projection and a co-operating depression formed one on said band and one on said inner casing.

45 9. A hydraulic shock-absorber comprising an end-plate, an inner casing mounted thereon and constituting a main working chamber for the reception of a working liquid, a vane in said chamber, a spindle secured to said vane and projecting from said chamber, a co-operating abutment secured in said chamber, which vane and which abutment divide the said chamber into two parts, and which abutment is located in the upper part of said chamber and is in engagement with said casing over its top surface, two air-vent passages, formed in said abutment, each opening on one end through said top surface, one communicating with one said part of the working chamber and the other communicating with the other said part, two air-release valves provided in said inner casing and located

50 55 60 65 one in alignment with each said air-vent

passage, at least one liquid admission valve provided in said inner casing and located towards the bottom thereof, and an outer casing, constituting a recuperator chamber, which casing is so mounted on said end-plate that the working chamber is nested in the recuperator chamber.

70 10. A hydraulic shock-absorber comprising an end-plate, an inner casing mounted thereon and constituting a main working chamber for the reception of a working liquid, a vane in said chamber, a spindle secured to said vane and projecting from said chamber, a co-operating abutment secured in said chamber, which vane and which abutment divide the said chamber into two parts, a passage extending through said abutment from one part of said chamber to the other part, a screw-threaded needle-valve in the abutment, which valve reaches into said passage and extends through said casing so that it can be adjusted from without the latter, an outer casing constituting a recuperator chamber, which casing is so mounted on said end-plate that the working chamber is nested in the recuperator chamber, a filling orifice formed in said outer casing in alignment with said needle-valve so that the latter can be adjusted through it, and means for automatically keeping the working chamber charged with working liquid from the recuperator chamber.

mounted thereon and constituting a main working chamber for the reception of a working liquid, a spindle extending outwardly from said chamber, a vane in said chamber 5 having a round boss on said spindle, a co-operating abutment formed by dividing a cylinder, whereof the external diameter is equal to the internal diameter of the inner casing and the internal diameter is equal to 10 the external diameter of the boss, along radial planes into a plurality of similar blocks, each of which constitutes one abutment and has two concentric cylindrical walls and two radial walls, which abutment is secured in 15 said chamber, an outer casing constituting a recuperator chamber, which casing is so mounted on said end-plate that the working chamber is nested in the recuperator chamber, and means for automatically keeping the 20 working chamber charged with working liquid from the recuperator chamber.

In testimony whereof I affix my signature.
ERNEST WILLIAM JOHNSON.
